CIRCULAR KNITTING MACHINES OF THE SUPER-IMPOSED NEEDLE CYLINDER TYPE
 Frederick Edward Deans and Carlyle Herbert Wainwright, Leicester, England, assignors to The Bentley Engineering Company Limited, Leicester, England
 Filed Sept. 1, 1959, Ser. No. 837,550
 5 Claims. (Cl. 66—14)

This invention is for improvements in circular knitting machines of the superimposed needle cylinder type and relates to an improvement in or modification of the invention forming the subject of U.S. Patent No. 2,910,847. Like the said earlier invention the present invention is concerned with circular knitting machines of the type (hereinafter referred to as "the type specified") having superimposed co-axial needle cylinders arranged to rotate and equipped with double ended needles, and sliders in each cylinder for operating said needles for knitting and for transferring needles between said cylinders to alter the character of the fabric, and having stationary cam boxes, one for each cylinder, for actuating the sliders in their knitting and transferring motions. Reference is directed to said earlier Patent No. 2,910,847 for information of the general problems involved when one of the needle cylinders (in that case the top cylinder) is provided with an extension to accommodate patterning instruments. It has been found to be advantageous in some cases to arrange that the bottom cylinder is the one having the extension, and closely similar problems arise also in that case because the bottom cam boxes must be spaced upwardly from the normal underneath mounting of the bottom cylinder in order to allow room for the patterning mechanism to act on the instruments in the lower part of the bottom cylinder forming its extension. The present invention has for an object to adapt the same principles used in said earlier invention for use with a machine having an extended bottom cylinder.

In accordance with the invention there is provided a knitting machine of the type specified wherein the bottom cylinder is extended beyond the length required for the knitting and transferring movements of the bottom sliders and is equipped within its extension with additional instruments for actuating the sliders under the dictates of patterning mechanism operable on the instruments, the bottom cylinder together with its extension being rotatably supported on a stationary support by a bearing at or near the lower end of such extension so as to upstand from such bearing, and wherein the bottom cam box is also supported from said stationary support in such manner as to permit the patterning mechanism to act on the additional instruments. As in the previous constructions referred to, the invention avoids the need for providing an intervening supporting plate to form a mounting for one of the cam boxes at a position located between the normal top and bottom plates by which the cylinders are supported rotatably.

In carrying out the invention there may be cam box supporting means extending upwards exteriorly of the bottom cylinder extension directly from the said stationary support to the cam box, said supporting means having at least one gap or aperture permitting the patterning mechanism to act on the instruments. In carrying out the invention in this manner the mounting of the bottom cam box will correspond to the mounting described in said Patent No. 2,910,847 for the top cam box, except that it is in a completely inverted attitude. In a preferred arrangement however the support of the cam box from said stationary support is obtained through the bottom cylinder and its extension. These provisions and other features of the invention are incorporated in the knitting

machine constructions which will now be described in detail with reference to the accompanying drawing in which:

FIGURE 1 is a perspective view of the upper part of the machine in one form of construction;

FIGURE 2 is a sectional view in a vertical plane through the cylinder, cam box and bedplate, taken on the line II—II of FIG. 3.

FIGURE 3 is a sectional plan view taken on the line III—III in FIG. 1.

FIGURE 4 is a part-sectional elevation, and

FIGURE 5 is a sectional plan on the line V—V of FIG. 4 showing means for adjusting the axial alignment of the bottom cam box,

FIGURE 6 is a view similar to FIG. 1 showing an alternative method of supporting the cam box assembly, and

FIGURE 7 is a detail view taken in section through the cylinder walls to show the needle sliders and instruments.

In FIG. 1 sufficient of the knitting machine is shown to permit of its being identified as a machine of the type specified. Attention is directed to the top and bottom needle cylinders, 1, 2, their respective cam boxes 3, 4 and the bed 5 of the machine (on which the bottom cylinder 2 is rotatably supported). The top cam box 3 contains various knitting and transferring cams of conventional type (not shown) to act on top needle sliders 42 (FIG. 7) and is secured through the medium of its cam box plate 6 to the top gear housing 7, which in turn is attached to the top bed plate 8, in known manner.

The bottom cylinder 2 has a triced downward extension 2a extending beyond the length necessary merely to accommodate the bottom sliders 43 shown in FIG. 7 and to provide for their knitting and transferring movements, this extension 2a being equipped with slidable patterning jacks 44 and 45 (FIG. 7) of a kind themselves well known. These jacks are adapted to be acted upon by any known form of patterning mechanism, one form of which is indicated generally at 9 by chain dotted lines.

The patterning mechanism, when operated, slides the jacks and brings them into and out of the range of patterning cams disposed within a jack cam box 10 which is a detachable part of the bottom cam box assembly. The patterning cams impart additional movements to the jacks so that the latter in turn impart, to the sliders, movements which differ from those imparted to the latter by the normal knitting and transferring cams.

The bottom cylinder 2 is attached to and rotatably supported by the gear carriage 11, FIG. 2 which has its bearing through the thrust race 12 in the bottom bed plate 5. Towards its upper end the cylinder 2 is provided with an external peripheral bearing flange 13, FIG. 2 to engage in a bearing groove provided by the bottom cam box assembly. This assembly shown in FIG. 2 comprises the bottom cam box 4 which is attached by screws 14 to an intermediate plate 15 to the underside of which is attached by screws 16 the jack cam box 10. The ring or bearing plate 17 is housed in the intermediate plate 15 and supports the entire assembly on the flange 13 of the cylinder 2. A ring 18 is provided in the jack box 10 to prevent any upward movement of the cam box assembly due to the thrust resulting from the action of the sliders and jacks on the cams in their respective cam boxes. The peripheral bearing flanges 13 may readily be arranged to extend completely around the bottom cylinder, but it need only be provided at say three or more intervals spaced apart around the cylinder, so as to present means locating the cam box height wise on the cylinder while permitting relative rotation between the cylinder and cam boxes. If reference is made to FIG. 1 it will be noted that the bottom cam box 4 and jack box 10 are conveniently sectioned as shown by the gaps

4a and 10a respectively, to facilitate assembly and dismantling. The sections are of course arranged to interfit in proper registry. The bearing flange 13 on the bottom cylinder may for practical convenience be formed integrally with the cylinder; machining of the cylinder being performed so as to provide the outwardly directed flange of appropriate dimensions projecting from its surface there-around or at intervals there-around. This manner of making the cylinder will involve cutting the tricks (indicated at 19, FIGS. 2 and 3) therein so as to extend through the bearing flange 13, but this will not interfere with the functioning of the flange for supporting the cam box assembly and may for certain purposes not requiring mention herein be advantageous.

In carrying out the invention there may be provided anchoring means additional to the said supporting means for preventing rotation or partial rotation of the bottom cam box assembly. The machine may include centering means for centering the cam box with respect to the axis of the bottom cylinder and such centering means may be constituted by or incorporated in the anchoring means just referred to. FIGS. 1 and 3 illustrate a typical example of such construction. It may be mentioned at this point, that while it is possible to permit the cam box assembly to center itself on the cylinder 2 or its extension 2a, yet, in certain eventualities (for example in transferring a considerable number of needles) loads may be thrown on the cylinder 2 tending to force its tricks out of alignment with the tricks in the cylinder 1 and it is desirable to center the cam box assembly independently of the cylinder 2 and to so arrange matters that when such loads occur the cam box assembly acts as a steady or bearing for the cylinder 2.

In the illustrated construction there are three torque rods 20, 21, 22, all of which extend tangentially with respect to the axis of the machine and, at one end they are each attached by screws 34 to the intermediate plate 15 of the cam box assembly whilst at the other to stationary supports. As shown rods 20, 21, 22, are each mounted on pillars 23, 24, 25, respectively forming the stationary supports. The joints 26, 27, 28, at which the respective torque rods are connected to the intermediate plate 15 are approximately equi-distant around the cam box assembly and it will readily be appreciated that the construction illustrated not only prevents rotational movement of the cam box assembly but also prevents any lateral movement of it.

Means is provided for the rotational adjustment of the cam box assembly and for its lateral adjustment. To this end the rods 20, 21, 22 are mounted on eccentric bosses 29 on collars 30 (FIGS. 4 and 5) carried by the respective pillars, the collars 30 being rotatable except when held in place by the clamping screws 31. Locating collars 32 are provided above the rods, these being held in place by their clamping screws 33. By suitable rotation of one or more of the collars 30, the eccentric bosses can determine the position of the axis of the cam box assembly relatively to the general axis of the machine and also its rotational adjustment.

As mentioned earlier, in an alternative construction in accordance with the invention the cam box assembly may be supported on struts or legs. FIG. 6 illustrates one such strut. Other struts may be provided, to make up a total of say three or four, at convenient intervals around the cylinder. As can be seen these supports comprise a

small bracket 134 attached by a screw or screws 35 to the bed 5 of the machine. A screwed pin 36 forms a hinge supporting the leg or strut 37, the upper end of leg 37 being drilled and tapped to take a threaded adjustable eye-bolt 38 which is hinged in the fulcrum post 39 by the screwed pin 40. Fulcrum post 40 is itself screwed into the intermediate plate 15 of the cam box assembly and locked by a nut 41. The height of the cam box assembly can easily be adjusted by removing the pin 40 and revolving the eye bolt 38 to increase or decrease the distance between the top and bottom hinges. In similar fashion i.e. by removing said pin 40 each leg 37 may be swung away from the cylinder at any time to give access to the cylinders and cam boxes etc.

What we claim is:

1. In a circular knitting machine, the combination comprising upper and lower coaxial needle cylinders equipped respectively with top and bottom needle sliders for knitting and transferring movements, a part of the bottom cylinder extending beyond the length required for the knitting and transferring movements of said bottom sliders, instrument means within said extending part for actuating said sliders, a patterning mechanism controlling said instrument means, supporting means by which said top cylinder is rotatably mounted, a stationary support at the lower part of said extended bottom cylinder, a bearing on said stationary support and rotatably mounting said bottom cylinder so as to upstand from said bearing, a bottom cambox, means supporting said bottom cambox from said stationary support merely against vertical thrusts and in such manner as to afford space for said patterning mechanism to act on said instrument means, fixed anchorages spaced apart around said bottom cambox, and anchoring means coupling said bottom cambox to said fixed anchorages to resist lateral and rotational thrusts on said cambox.

2. The combination according to claim 1 wherein said means supporting said cambox from said stationary support is formed by upstanding struts extending exteriorly along the said extending part of said bottom cylinder directly from said stationary support to said bottom cambox and providing spaces permitting said patterning mechanism to act on said instrument means.

3. The combination according to claim 1 wherein the said means supporting said bottom cambox from said stationary support is constituted by an external peripheral bearing projection on said bottom cylinder and an interengaging grooved ring provided in said cambox.

4. The combination according to claim 1 wherein said fixed anchorages are constituted by pillars connecting said supporting means for said top cylinder with said stationary support for said bottom cylinder and the said anchoring means are constituted by tangential rods each connected at one end to said cambox and at the other end to one of said pillars.

5. The combination according to claim 1 having means for adjusting said anchoring means to provide for rotational and lateral adjustment of said cambox.
